UNITED STATES PATENT OFFICE.

HAROLD N. HANSEN, OF HIGHWOOD, ILLINOIS, ASSIGNOR TO HENRY GIESSEL COMPANY, OF CHICAGO, ILLINOIS, A CORPORATION OF ILLINOIS.

VENTILATOR.

Application filed July 10, 1925. Serial No. 42,725.

This invention relates to improvements in ventilators and has for its object to provide a ventilator which may be readily attached to the roof of a passenger car or to any enclosed chamber to be ventilated. My improved ventilator is constructed in such wise as to produce an efficient exhaust of air from the space being ventilated and so as to prevent the entrance of back drafts, moisture, dirt, cinders or the like into such space. Another advantage resides in the ability to manufacture my ventilator at relatively low cost. This and other objects and advantages will be more fully set forth and described in the following specification and shown in the accompanying drawings in which,

Fig. 1 is a plan view of a passenger car showing my ventilators attached to the clear-story thereof;

Fig. 2 is a vertical section along the line 2—2 of Fig. 1;

Fig. 3 is an enlarged plan view of my ventilator, a portion of the casing being broken away for clearness;

Fig. 4 is a vertical section along the line 4—4 of Fig. 3;

Fig. 5 is a vertical section through an adapter showing the method of attachment of the same to the inclined deck of a car, the ventilator being indicated in dotted outline;

Fig. 6 is a front elevation of the adapter shown in Fig. 5;

Fig. 7 is a plan view of a modified form of ventilator;

Fig. 8 is a vertical section along the line 8—8 of Fig. 10 showing another modified form of ventilator;

Fig. 9 is a similar section taken along the line 9—9 of Fig. 10;

Fig. 10 is a front elevation of the modified form of ventilator shown in Figs. 8 and 9, a portion of the ventilator being broken away for clearness;

Fig. 11 is a plan view of this form of ventilator, a portion of the casing being broken away for added clearness.

Like numerals refer to like elements throughout the drawings in which 10 indicates generally a railway car having the deck 10^a, upper deck 10^b and clearstory 10^c connecting the two levels, the latter being provided with ventilating ports or windows 10^c at suitable locations. 11 indicates generally one form of my ventilator comprising the entrance port 11^a, surrounded by the collar 11^b

insertable into the window or ventilating port of the clearstory 10^c. Projecting outwardly around the port 11^a is the attachment collar 11^b provided with suitable screw or rivet holes. 11^c indicates the rear or inner 60 wall of the ventilator 11 in which is formed the entrance port 11^a at the upper portion, as shown in Fig. 4 for example. The ventilator is provided with the outwardly and downwardly curved upper wall or roof 11^e, 65 forming with the end walls 11^f and rear wall 11^d a passage or chamber for the passage of air being exhausted, a partial bottom wall 11^g co-operating in the formation of such passage or chamber. 11^h indicates the outer or front 70 wall extending between the upper walls 11^f and outwardly spaced from the bottom 11^g and the curved upper wall 11^e to form a vertical discharge passage or duct indicated by numeral 11ⁱ. The upper portion of the outer 75 wall 11^h is extended upwardly above the lower edge of the roof or upper wall 11^e as indicated in Fig. 4, while the lower portion of the curved roof 11^e is extended downwardly below the top of the side walls 11^f and curved 80 outwardly as indicated at 11^k, (see Fig. 4). Extending from the front or outer wall 11^h to the inner or rear wall 11^d are the vertical partitions 11^m having their lower edges substantially co-planar with the lower edges of 85 the side, front and rear walls. These partitions 11^m are preferably extended upwardly into the space beneath the curved roof 11^e to a point in the same plane as the lower edge of entrance port 11^a. 90

In the form shown in Figs. 1 to 4, for example, the partition plates 11^m are cast integral with the main body of the ventilator 11 and the bottom plate 11^g is made detachable to permit the casting of the balance of the 95 structure, being secured through the medium of lugs 11ⁿ and screws 13 to the side and rear walls of the ventilator.

The ease of attachment to and detachment from the ventilating or window ports of the 100 clearstory of the car is obvious. The partitions 11^m intensify the draft or eduction of the air from the car or other chamber, and at the same time prevent or substantially prevent the entrance of cross-currents or back 105 drafts, as well as cinders, dust, rain or the like. The upward extension of the wall 11^h, as shown in Fig. 4, and the downward extension or continuation 11^k of the curved top wall also assist to prevent entrance of back 110

drafts or the like. Should rain, cinders or the like make their way into the ventilator beneath the upper wall 11^e they will be precipitated on the inclined bottom plate 11^g and roll or fall off out through the bottom of the vertical passage 11^l. I prefer to arrange the ventilator in the manner shown in Fig. 2 for example spaced above the deck 11^a of the car so that the air being traversed by the ventilator and car will set up eduction currents above and below the ventilator passage 11^l. By extending the partitions 11^m upwardly into the passage beneath the curved roof 11^e added resistance or obstruction to the entrance of longitudinal back currents is provided.

In Figs. 5 and 6 I have shown means and a method of attaching ventilator 11 to the inclined deck 10^a of a car or the like. To effect this method of attachment, I provide what is termed an adapter or coupler generally indicated by numeral 15 which comprises a casing having the inlet port 15^a around which extends the inclined attachment collar 15^b which is suitably apertured for attachment to the inclined deck of the car by means of bolts, screws or the like. The adapter is provided with a plane front wall 15^c having the aperture 15^d therein. Supporting lugs 15^e project from the sides into the opening 15^a. A flange 15^f extends around three sides of the opening 15^a and is suitably apertured at 15^g to permit insertion of fastening screws through the flange 15^f and into the corresponding apertures in the flange 11^e of the ventilator 11. The latter is mounted as indicated in dotted lines in Fig. 5 with its neck 11^b projecting into the opening 15^a and resting upon the lugs 15^e, and is secured in place by suitable fastening screws as indicated above. The function is similar to that described above save that the exhaust air is drawn out or passes out through aperture 15^d before it reaches the ventilator 11. In Fig. 7 I have shown another modified form in which the end walls 11^x of the upper or curved roof portion of the ventilator converge from the clearstory outwardly. Similarly the end walls 11^y of the lower portion of the ventilator are also convergently arranged but with a lesser degree of inclination, although such inclination may be varied as to both parts of the ventilator to meet conditions and requirements. In the form shown in Fig. 7 a difference in the angle of convergence of the walls 11^x and 11^y necessitates provision of an outwardly inclined connecting web 11^z as shown in Fig. 7. The construction and operation of this form of my ventilator is substantially similar to that of the form previously described save that the air impinging upon the end walls of the ventilator does not encounter the same in a relatively perpendicular direction but at an angle so that the resistance is less and there is an added re-direction of the

air glancing off the end walls 11^x and the connecting webs 11^z over the upper end of the exhaust passage 11^l.

In Figs. 8 to 11 I have illustrated still another form of my invention in which the construction is generally similar to that of the form of Figs. 1 to 4 save that the front and rear walls 11^h and 11^d respectively are provided with the vertical ribs 11^r which are provided with V-shaped seats or grooves 11^s. A central partition 11^m is retained cast integral with the body of the ventilator but the other partitions 11^t are formed of light sheet metal as copper with the ends 11^w rearwardly bent or inclined to permit seating in the grooves 11^r, preferably so that some force is required for insertion or removal to ensure retention in proper position and to prevent rattling. In this form the partition sheets 11^t are provided with upper and lower outwardly struck tongues 11^v, 11^w respectively, forming longitudinal ports or apertures 110 in the sheets. Back currents making their way into the spaces between the partitions 11^t will encounter these tongues 11^v, 11^w, affording a resistance from further passage and eddying or baffling them. At the same time it is believed that these tongues constricting as they do the passage between the partitions enhances the eduction action. In this form the bottom plate 111 is also formed of light sheet metal with its front and rear edges 111^a reversely bent. The plate is preferably attached by fastening screws 112 extending through the plate into suitable apertured fastening bosses 113 formed integral with the front and side walls of the ventilator 11.

Save as stated above the function of this ventilator is generally similar to that shown in Figs. 1 to 3 described above.

It will be obvious that my invention is susceptible to other modifications and I do not wish to be restricted to the form shown and described save as defined in the appended claims.

What I claim is:

1. A ventilator having an entrance port in one plane, exhaust outlets with an outlet passage extending therebetween, said outlets being in planes angularly disposed with respect to the plane of said entrance port and a passage extending between and connecting said entrance port and said outlet passage, and vertical partitions substantially parallel to the ends of said ventilator located in said first passage and extending the distance between said outlets.

2. A ventilator having an entrance port in one plane, exhaust outlets with an outlet passage extending therebetween, said outlets being in planes angularly disposed with respect to the plane of said entrance port, and a passage extending between and connecting said entrance port and said first named passage, and vertical partitions located in said outlet

passage and extending upwardly into said second passage.

3. A ventilator provided with front, rear and side walls, a downwardly and outwardly directed top wall extending between said side walls, said ventilator being open between said top wall and said front wall to form a discharge opening said rear wall being extended beyond the limits of said front wall and having an inlet port above said discharge opening.

4. A ventilator comprising a casing formed with end walls, a front wall, a rear wall and a top wall, said casing being provided with a discharge opening adjacent the upper portion of said front wall and being further provided with an entrance port in the rear wall located above the discharge opening and offset with respect to said discharge opening.

20 5. A ventilator comprising a casing formed with front, rear and end walls and a top wall, said casing being further provided with a discharge opening adjacent the upper portion of the front wall and an entrance port in the rear wall above the level of said discharge opening, said casing being further provided with a bottom wall extending outwardly from the rear wall, and partitions extending from said front to said rear wall.

30 6. A ventilator comprising a casing formed with front, rear and end walls and a top wall, said casing being further provided with a discharge opening adjacent the upper portion of the front wall and an entrance port in the rear wall above the level of said discharge opening, said casing being further provided with

a bottom wall extending outwardly from the rear wall, and partitions extending from said front to said rear wall, said partitions extending upwardly into the space beneath said top wall.

7. A ventilator comprising a casing formed with front, rear and end walls and a top wall, said casing being further provided with a discharge opening adjacent the upper portion of the front wall and an entrance port in the rear wall above the level of said discharge opening, said casing being further provided with a bottom wall extending outwardly from the rear wall, and partitions extending from said front to said rear wall, said partitions being removably mounted in said casing.

8. A ventilator comprising a casing with side, top, front and rear walls, said front and rear walls being provided with grooves, partition plates extending between and seated in said grooves, said partitions being provided with reversely bent edge portions located in said grooves.

9. A ventilator comprising a casing having an entrance port and a discharge opening, said ventilator being provided with a connecting passage between said port and opening and being further provided with means attachable to the clearstory of a car or the like, and an adapter comprising a conduit, said adapter being attachable to the deck of a car and detachably engageable by said ventilator to align said port with said conduit.

In witness whereof, I hereunto subscribe my name to this specification.

HAROLD N. HANSEN.

CERTIFICATE OF CORRECTION.

Patent No. 1,691,283.

Granted November 13, 1928, to

HAROLD N. HANSEN.

It is hereby certified that error appears in the printed specification of the above numbered patent requiring correction as follows: Page 3, line 6, claim 3, after the word "open" insert the words "at top and bottom"; and that the said Letters Patent should be read with this correction therein that the same may conform to the record of the case in the Patent Office.

Signed and sealed this 8th day of January, A. D. 1929.
